(57) **CLAIM**

The ornamental design for a mobile device mount clip assembly, as shown and described.

DESCRIPTION

FIG. 1 is a perspective view of a mobile device mount clip assembly;

FIG. 2 is a top plan view thereof;

FIG. 3 is a bottom plan view thereof;

FIG. 4 is a right-side elevational view thereof, the left-side elevational view being a mirror image;

FIG. 5 is a front elevational view thereof;

FIG. 6 is a rear elevational view thereof;

FIG. 7 is a perspective view of the bottom portion of the mobile device mount clip assembly;

FIG. 8 is a front elevational view thereof, the rear elevational view being a mirror image, the left-side elevational view being a mirror image, the right-elevational view being a mirror image;

FIG. 9 is a top plan view thereof;

FIG. 10 is a perspective view of the top portion of the mobile device mount clip assembly;

FIG. 11 is a bottom plan view thereof;

FIG. 12 is a front elevational view thereof, in which a sectional view is taken and shown in FIG. 13; and,

FIG. 13 is right-side elevational view thereof.
